Attorney:

UNITED STATES PATENT OFFICE

WILLIAM E. WINE, OF TOLEDO, OHIO

RAILWAY HOPPER CAR

Application filed September 2, 1930. Serial No. 479,365.

My invention relates to railway hopper cars and has for its principal object the provision of improved means for connecting the hood of the center sill of this type of car with the splice sheet employed for joining slope sheets disposed on opposite sides of the center sill.

A primary feature of the invention consists in providing, in combination with a hopper car having a center sill hood provided with downwardly diverging portions, a splice sheet for connecting slope sheets of the car disposed on opposite sides of the center sill, the splice sheet being provided with offset portions arranged in overlapping relation to the diverging portions of the center sill hood.

Another feature of the invention consists in providing, in combination with a hopper car having a center sill hood provided with downwardly diverging portions, a splice sheet for connecting inclined floor sheets of the car which are disposed on opposite sides of the center sill, the splice sheet being provided with upwardly converging portions overlappingly secured to the diverging portions of the center sill hood.

A further feature of the invention consists in providing a splice sheet for the slope sheets of a railway hopper car having a plate portion adapted to be secured to the slope sheets and having angularly disposed upwardly converging portions adapted to be arranged in overlapping relation to the longitudinal hood sheet of the car.

Other and more specific features of the invention residing in advantageous forms, combinations and relation of parts will herein-after appear and be pointed out in the claims.

In the drawings illustrating a preferred embodiment of the invention:

Figure 1 is a plan view of a portion of a railway hopper car.

Figure 2 is an enlarged sectional view taken on line 2-2, Figure 1.

Figure 3 is a fragmentary sectional view taken on line 3-3, Figure 2.

Figure 4 is a plan view of the splice sheet, the view being taken at right angles to the major portion of the sheet.

Figure 5 is a side view of the splice sheet as viewed in Figure 4.

Figure 6 is an end view of the splice sheet, the view showing the sheet in the position in which it occupies when applied to a hopper car.

The hopper car chosen for purposes of illustrating the invention is, in general, of usual construction comprising a bolster 1 and a center sill 2. As is common practice the center sill is formed by two beams 3 and a top cover plate 4. Embracing the upper portion of the center sill is a hood sheet 5 having downwardly diverging portions 6 which terminate in substantially vertical flanges 7 and are secured by rivets 8 to the sides of the center sill. The hood sheet, as is well known, serves to prevent granular lading such as coal and the like from lodging on the top of the center sill deflecting such lading onto opposite sides of the latter.

The floor of the car adjacent its ends inclines downwardly and inwardly and may be formed in part by a slope sheet 9 which extends from an end of the car to the bolster, being overlappingly secured to the latter by rivets 10. Extending downwardly from the bolster on opposite sides of the center sill are the inclined floor or slope sheets 11. At their upper portions these sheets are interposed between the slope sheet 9 and the top of the bolster, being secured to each by the rivets 10. These sheets extend downwardly below the top of the center sill and constitute the chute sheets of the hoppers 12 which, in addition to the chute sheets, are formed by inner and outer side sheets 13 and 14, respectively. These side sheets are formed with inturned flanges 15 which underlap and are rigidly secured by rivets 16 to the slope sheets 12.

Above the center sill the slope sheets 11 are connected by a splice sheet 17 having a main

plate portion 18 arranged in overlapping relation to adjacent portions of the slope-sheets and rigidly secured thereto by rivets 19. The upper portion of the splice plate is formed 5 with a tongue or extension 20 offset downwardly from the plane of the plate portion 18 so as to be interposed between the slope sheet 9 of the top of the bolster for connection thereto by rivets 21. Thus it will be seen that 10 although the plate portion 18 of the splice plate overlies adjacent portions of the slope sheets 11 the tongue or extension 20 of the splice sheet underlies the slope sheet 9. The lower portion of the splice sheet is formed 15 with upwardly converging portions 22 which intersect in a substantially horizontal line below the upper edge of the splice sheet. These diverging portions 22 are disposed in planes parallel with the longitudinal axis of 20 the car and are rigidly secured by rivets 23 in overlapping relation to the diverging portions 6 of the center sill hood. The lower edges of the diverging portions 22 are connected to adjacent parts of the plate portion 25 18 of the splice plate by substantially vertical portions 24 adapted to overlap the adjacent flanges 7 of the hood sheet. By forming the splice plate with an offset having angularly disposed portions adapted to be arranged in 30 overlapping relation to the hood sheet it will be perceived that the latter may be easily and conveniently secured to the splice sheet without the necessity of offsetting and flanging the hood sheet as has heretofore been customary. 35 Furthermore it will be observed that the hood sheet may extend all the way under the offset portion of the splice sheet and even project therebeyond. This obviates the necessity of accurately fitting the hood sheet to the 40 splice sheet and also the necessity of employing a hood sheet of a definite and fixed length. Furthermore those skilled in the art will appreciate that a relatively small sheet such as the splice sheet may be more easily formed 45 into a desired configuration or shape than a relatively large pressing or sheet such as a center sill hood sheet.

I claim:

1. In a railway hopper car, the combination 50 with a center sill having a hood provided with downwardly diverging portions, of a body bolster, slope sheets extending downwardly from the body bolster on opposite sides of the center sill, a splice sheet 55 extending downwardly from the bolster and connecting the slope sheets above the center sill, the lower portion of said splice sheet having offset portions arranged in overlapping relation to the downwardly diverging portions of the center sill hood.
2. In a railway hopper car, the combination 60 with a center sill having a hood provided with downwardly diverging portions, of a body bolster, inclined floor sheets extending downwardly from the body bolster

on opposite sides of the center sill, a splice member having a downwardly inclined plate portion rigidly secured to portions of the floor sheets above the center sill, the lower portion of said member being provided with upwardly converging portions overlappingly secured to the diverging portions of the center sill hood.

3. In a railway hopper car, the combination 70 with a center sill, of a hood sheet having downwardly diverging portions respectively terminating in substantially vertical flanges rigidly secured to the sides of the center sill, of inclined floor sheets extending downwardly from above the center sill on opposite sides of the latter, an inclined splice sheet rigidly connecting said floor sheets, the lower portion of the splice sheet being provided with upwardly extending substantially vertical portions arranged in overlapping 80 relation to the flanges of the hood sheet and with upwardly converging portions arranged in overlapping relation to the diverging portions of the hood sheet.

4. In a railway car, the combination with 90 a center sill having a hood sheet provided with downwardly diverging portions, of a body bolster, slope sheets extending downwardly from the body bolster on opposite sides of the center sill, and a splice sheet 95 extending downwardly from the bolster connecting portions of the slope sheets above the center sill, the lower portion of the splice sheet terminating in a portion forming with the top of the center sill a pocket for receiving the adjacent end of the hood sheet whereby the latter may extend beyond the splice sheet toward the neighboring end of the car.

5. In a railway hopper car, the combination 100 with a center sill having a hood provided with downwardly diverging portions, of a body bolster, slope sheets extending downwardly from the body bolster on opposite sides of the center sill, and a splice sheet extending downwardly from the body 105 bolster toward the center sill and being secured to the slope sheets on opposite sides of a vertical plane passing through the line of intersection of the plane of the slope sheets and a horizontal plane passing 110 through the top of the center sill, said splice sheet having upwardly converging portions secured in overlapping relation to the diverging portions of the center sill hood.

6. In a railway hopper car, the combination 115 with a center sill having a hood, of a bolster, a slope sheet extending downwardly from the end of the car to adjacent the bolster, additional slope sheets extending downwardly from the bolster on opposite sides of the center sill, the second-named slope sheets being interposed between the first-named slope sheet and the top of the bolster and being rigidly secured to the latter, a splice sheet extending downwardly from the bol- 120

ster connecting the second-named slope sheets, the splice sheet having a portion extending between the adjacent edges of the second-named slope sheets and underlying 5 an adjacent portion of the first-named slope sheet, the lower central portion of the splice sheet being provided with upwardly converging portions arranged in overlapping relation to the center sill hood.

o In testimony whereof I affix my signature.
WILLIAM E. WINE.
